(57) **CLAIM**

We claim the ornamental design for a closure, as shown and described.

DESCRIPTION

FIG. 1 is a top perspective view of a first embodiment of a closure, showing our new design;

FIG. 2 is a bottom perspective view thereof;

FIG. 3 is a front view thereof, the right, back, and left views being largely the same;

FIG. 4 is a top view thereof;

FIG. 5 is a bottom view thereof;

FIG. 6 is a top perspective view of a second embodiment of a closure, showing our new design;

FIG. 7 is a bottom perspective view thereof;

FIG. 8 is a front view thereof, the right, back, and left views being identical;

FIG. 9 is a top view thereof; and,

FIG. 10 is a bottom view thereof.

The broken lines are shown for the purpose of illustrating parts of the article that form no part of the claimed design.

1 Claim, 10 Drawing Sheets
